UNITED STATES PATENT OFFICE.

ROBERT RENNICK, OF WOODFORD COUNTY, KENTUCKY.

IMPROVEMENT IN CAR-COUPLENS.

Specification forming part of Letters Patent No. 174,440, dated March 7, 1876; application filed January 6, 1876.

To all whom it may concern:

Be it known that I, ROBERT RENNICK, a resident of the county of Woodford, but having my post-office address at Keene, in the county of Jessamine and State of Kentucky, have invented a new and useful Improvement in Automatic Car-Couplers, of which the following is a specification:

In the annexed drawings, making a part of this specification, Figure 1 is a section, showing in plan the internal arrangement of parts. Fig. 2 is a vertical longitudinal section. Fig. 3 is an end elevation.

The same letters are employed in all the figures in the designation of identical parts.

A A are the draw-heads of a railway-car, chambered to receive two oscillating jaws, B B, sustained upon stems B' B', which are elastic, their tension tending to bring the jaws together. Beveled notches are cut on the opposed faces of the jaws to receive an arrow-headed shackle, the draft of the two being such that the strain upon the shackle tends to draw the jaws together. Links C C are fastened to the back of the jaws, and also to the short arms of levers D D, which are disposed on each side of the platforms, so as to permit passengers to pass without interruption. E is the shackle, being arrow-headed on each end, so that it may be attached to either car. The lower faces of the shackle may also be beveled off toward the end, forming a shoulder, by means of which the point of the shackle may be raised or depressed by means of the spring G and foot-rod F. The spring bears on the upper face of the end of the shackle, and sup-

ports it normally in a horizontal position; but by pressing on the foot-rod F the spring may be pressed on the end of the shackle, and raise its free end in case the draw-head of the approaching car is higher than the draw-head to which the shackle is attached. On the other hand, the free end may be depressed by lifting the spring, so as to relieve the pressure on the end of the shackle.

The cars will be coupled by running together, or uncoupled by pressing against the levers D, or they will become defached automatically in case one car should leave the track, so as to deflect the shackle to an angle of about forty-five degrees. By making holes in the top and bottom of the draw-head to receive coupling-pins the car may be connected to the ordinary cars by a link.

Spring-plates H H are also inserted in the bottom of the draw-head, to permit the end of the shackle to be forced down in order to raise the free end.

What I claim as my invention, and desire to secure by Letters Patent, is—

In combination with the draw-head and shackle, the springs G and H and foot-rod F, for controlling the shackle in coupling, substantially as set forth.

In testimony whereof I have signed my name to this specification in the presence of two subscribing witnesses.

ROBERT RENNICK.
